ELECTRON TUBE MOUNT

Roy K. Wolke, Maplewood, and Frank J. Pilas, Lyndhurst, N. J., assignors to Radio Corporation of America, a corporation of Delaware

Application January 4, 1956, Serial No. 557,288

11 Claims. (Cl. 313—6)

The present invention is concerned with the art of electron tube mounts, and relates in particular to improvements in electrode cages for such mounts. Electrode cages of electron tubes commonly include electrodes that comprise at least a cathode and an anode, and a pair of insulating spacer plates sandwiching these electrodes between them for positioning the electrodes in a desired relation with respect to each other.

Previous plural cage electron tubes have usually had all of the components thereof assembled into a single, plural cage structure in a manner wherein a defective or missing component in any one of the cages resulted in a scrapping of the entire structure. Typically, such prior structures have had all of the electrodes of the separate cages mounted between a single pair of spacer plates. The practice of mounting the electrodes of all of the cages between a single pair of spacer plates has required the use of relatively complicated and costly machinery in automatically assembling such structures. Since the loss due to scrapped assemblies increases geometrically with the number of the parts in the assembly, it is desirable to assemble the relatively complex plural cage structures referred to by integrating relatively simple subassemblies (each of which may be comprised of a complete cage which may be separately tested and scrapped if imperfect) into plural cage structures. However, prior electrode cages do not readily lend themselves to integration in a multi-cage structure by available assembling techniques.

It is therefore an object of the invention to provide an improved plural cage structure for an electron tube which lends itself to relatively low cost assembling techniques.

It is another object of the invention to provide in an electron tube an improved plural cage structure that is comprised of relatively simple, self-supporting sub-assemblies structures.

The foregoing and related objects are accomplished in an electron tube structure including two elongated, side-by-side electrode cages each having two spacer plates. One of the spacer plates of each cage has a transverse extent spanning only one of the cages. The other of the spacer plates has a longer transverse extent spanning both of the cages and serves to fix the two cages into a unitary structure.

In making such a plural cage structure the two cages are separately assembled into two self-supporting units, and then the units are positioned with the longer spacer plate of each cage lapped over the surface of the shorter spacer plate of the other cage to form a composite, self-supporting structure. The double spacer plate thicknesses thus formed may be positioned on opposite sides of the tube for increasing ruggedness and for decreasing microphonic noise production in the tube. The technique of first separately assembling the separate cages of the plural cage structure and then integrating the sub-assemblies thus formed into a complete plural cage structure is of

2

particular advantage. This advantage resides in the fact that presently available machines, which are used for making single self-supporting cage units, may be used for making each of the two cages included in the composite structure. The use of available machines is feasible due to the fact that each individual cage of a multiple cage structure according to the invention is a self-supporting structure.

The invention is described in greater detail in the drawing where like numerals refer to like parts, and wherein:

Fig. 1 is a partially cut-away side elevational view of an electron tube mount incorporating the invention;

Fig. 2 is an enlarged top plan view of one of the shorter spacer plates referred to and used in the mount of Fig. 1;

Fig. 3 is a view illustrating a step in the manufacture of the tube shown in Fig. 1; and

Fig. 4 is a fragmentary view of a portion of an electron tube embodying another aspect of the invention.

Fig. 1 illustrates an electron tube 2 having electrode access terminals or prongs 4 at one end thereof and an envelope 6 containing a plural cage mount 8 comprised of two like elongated, side-by-side cages, for example a triode and a tetrode cage, 10 and 12, respectively. Each of the cages 10 and 12 includes two relatively flat spacer plates 14, 16, 18, and 20, respectively. The triode cage 10 has, mounted between its two spacer plates 14 and 16, a cathode 22 surrounded by a wound grid 24, the grid 24 being made up of a pair of side rods 26 having a lateral grid winding 28. The grid 24, in turn, is surrounded by a sheet metal anode 30. The tetrode cage 12 has, mounted between its two spacer plates 18 and 20, a cathode 32 surrounded by a pair of concentrically wound grids 34 and 36 each having a pair of side rods, 38 and 40 respectively, and a lateral grid winding, 42 and 44 respectively. The grids 34 and 36, in turn, are surrounded by a sheet metal anode 46. Each of the electrodes referred to has a portion at each of its opposite ends, 22', 24', 32', 34', 35', and 46' respectively, extending through the spacer plates of its cage. The electrodes are maintained in position within the tube 2 by means of the plates 14, 16, 18, and 20.

The two spacer plates of each cage are spaced the same distance apart as the spacer plates of the other cage. One of the plates 16 and 18 of each cage is relatively short and has a transverse extent spanning only its own cage. The other of the plates of each cage, 14 and 20 respectively, are relatively long and each has a transverse extent spanning both of the cages and is lapped over the shorter plate of the other cage for fixing the cages into a plural-cage structure. Each of the two cages of the structure is consequently self-supporting and is adapted to be separately assembled at one location and transported to another location for integration into a composite, self-supporting multiple cage mount.

The double spacer plate thicknesses created at diagonally opposite ends of the plural cage mount effects an increased ruggedness of the tube by enabling the mount to better withstand stresses such as those caused by impact. Also, since each cage has a pair of spacer plates at one end, the double spacer plate thickness apparently gives rise to a relatively firm gripping of the electrodes by the plates. This gripping prevents the electrodes from moving relative to the plates and consequently reduces electrical disturbances caused by such motion.

Fig. 2 illustrates an enlarged top plan view of one of the shorter spacer plates, namely the shorter plate 18 of the second cage 12. This plate 18 has one aperture 48 adapted to receive the cathode extension portion 32'; a first pair of apertures 50, on opposite sides of the cathode receiving aperture 48, each adapted to receive one of the extension portions 34' of the inner grid 34; a second pair

of apertures 52, on opposite sides of the first apertures 50, each adapted to receive one of the extension portions 36' of the outer grid 36; and a third pair of apertures 54, on opposite sides of the cathode receiving aperture 48 and in a line at right angles with respect to a line passing through the first pair of apertures 50, each adapted to receive one of the extension portions 46' of the anode 46.

As shown in Fig. 3, the portion of the long spacer plate 14 adapted to span the short spacer plate 18 of the second cage 12 has similarly oriented apertures. Each of the apertures in the long spacer plate 14, which is adapted to receive the same electrode extension portion as a corresponding aperture in the short spacer plate 18, is indicated by a reference numeral corresponding to the reference numeral of the similarly oriented aperture in the short spacer plate. The other long spacer plate 20 also has apertures 56 and 58 to receive, respectively, the electrode extension portions 22' and 24' of the first cage. The apertures adapted to receive the extension portions of the anode of the first cage are not shown in the drawing.

Assembly of the cages

The two cages 10 and 12, after being separately assembled, are positioned with the long spacer plate 14 and 20 of each cage lapped over the surface of the short spacer plate, 18 and 16 respectively, of the other cage.

Fig. 3 illustrates the method by which the two cages 10 and 12 are assembled into a unitary plural cage mount. The cages are first positioned in axial alignment. By axial alignment of the cages there is meant axial alignment of the long spacer plates 14 and 20. The first cage 10 has its short spacer plate 16 facing downwardly and the other cage 12 has its short spacer plate 18 facing upwardly; the short spacer plates 16 and 18 of the cages are adjacent to each other and on opposite sides of a reference plane 60 parallel to the axes of the cages; and the spanning portion of each long spacer plate 14 and 20 is in axial alignment with the short spacer plate 16 and 18 of the other cage. By an axial alignment of the extension portions of the long spacer plates 14 and 20, each with the short spacer plates 16 and 18 of the other, there is meant an axial alignment of the apertures 48 to 58 in the spacer plates. Therefore, an axial alignment of a spanning portion of a long spacer plate with its spanned short spacer plate refers to an axial alignment of each of the electrode receiving apertures 48 to 58 of the spacer plates with each other.

One of the two cages, 12, is seated on an anvil 62 having recesses 64 and 66 each adapted to receive the electrode extension portions on one side of a cage (the lower electrode extension portions of, respectively, the first and second electrode cages 10 and 12 shown in the drawing). The long spacer plate 20 of the second cage 12 is supported by the upper surface 68 of the anvil 62. The first cage 10 is supported in axial alignment with the second cage 12 and above the anvil 62 by support means such as, for example, a suction holding mechanism of a transfer device of which only the suction holding member 70 is shown. When the suction holding member 70 is connected to a vacuum source, the upper cage is supported; when the inside 72 of the suction holding member 70 is connected to air at atmospheric pressure (after the cages 10 and 12 have been positioned in lapped relation) the cage 10 is released.

The cages 10 and 12 are moved axially toward each other until the electrode extension portions 22', 24', 32', 34', 36' and 46' each engages its corresponding aperture 48 to 58 of the adjacent spanning plate of the other cage, and the shorter spacer plate of each cage contacts the long or spanning plate of the other cage. After the spanning and spanned spacer plates of the two cages are in contact, and the electrode extension portions of each cage extend through the apertures in the adjacent spanning plate of the other cage, some of the electrode extending

portions (the anode extension portions 30' and 46' in the tube illustrated) which extend through the adjacent spanning plate are deformed, as by being bent in a transverse direction, for fixing adjacent spanned and spanning spacer plates together and thus integrating the two cages into a single mount.

Fig. 4 illustrates a tube 29 similar to that shown in Figs. 1 to 3 and illustrating another aspect of the invention. While at least one edge of each spacer plate in the tube of Figs. 1 to 3 engages a portion of the envelope, the short spacer plates may instead have a relatively small transverse extent. As shown in Fig. 4, a short spacer plate 16a may have a transverse extent sufficient to span the cage 10a, the spacer plate being spaced from the envelope 6a of the tube. Only the long spacer plate 20a in this tube engages a portion of the inside walls of the envelope. This arrangement, makes use of a smaller quantity of spacer plate material, and, since the spacer plate material is usually mica (a relatively costly material), consequently proves advantageous in the mass production of such tubes. Also, this arrangement allows the short spacer plate 16a referred to to be made in a shape having bilateral symmetry. This shape affords a greater degree of freedom of orientation in manufacturing the plural cage structure.

Thus it is seen that the invention provides an improved plural cage electron tube mount which lends itself to relatively low cost assembling techniques by being comprised of relatively simple, self-supporting sub-assembly structures.

What is claimed is:

1. An electron tube mount comprising two electrode cages each including two spacer plates, one of the plates of each of said cages extending substantially only across one of said cages and the other of the plates of each of said cages spanning both of said cages, whereby each of said cages is adapted to be separately assembled between said one of said plates and said other of said plates to form a separate self-supporting structure, and two of said structures are adapted to be fixed into a composite two-cage structure.

2. A plural cage structure comprising two electrode cages each including two flat spaced-apart spacer plates, one of the plates of each of said cages extending substantially only across one of said cages and the other of the plates of each of said cages having an extension portion spanning the other of said cages and with said extension portion of each of said other of said plates lapped over said one of said plates of the other cage, and each of said extension portions being fixed to the cage spanned by said portion, whereby each of said cages is adapted to be separately assembled between said one of said plates and said other of said plates to form a separate, self-supporting structure, and two of said structures are adapted to be fixed into a composite two-cage structure.

3. An electron tube mount comprising two elongated electrode cages each including at opposite ends two flat spaced-apart spacer plates, each of said cages having a plurality of electrodes each having portions extending through the plates of its cage, one of the plates of each of said cages extending substantially only across one of said cages and the other of the plates of each of said cages having an extension portion spanning the other of said cages and with said spacer plate extension portion of each of said cages lapped over said one of said plates of the other cage, the portions of the electrodes extending through each of the spanned plates also extending through its spanning plate extension portion for fixing the spanned and spanning spacer plates to each other.

4. A self-supporting electron tube cage adapted to be integrated with a like cage to form a composite, two-cage structure, said cage comprising an elongated electrode assembly having a spacer plate fixed to each end thereof, one of said plates having a transverse extent sufficient to span said cage and the other of said plates hav-

ing a transverse extent sufficient to span said cage and having an extension portion adapted to span at least a portion of a like cage positioned adjacent to said cage, whereby two of said cages are each adapted to be separately assembled between said two of said spacer plates to form separate, self-supporting cages and then fixed with the other cage into a composite structure.

5. A self-supporting electron tube cage adapted to be integrated with a like cage to form a composite, two-cage structure, said cage comprising an elongated electrode assembly having a spacer plate fixed to each end thereof, one of said plates having a transverse extent sufficient to span said cage and the other of said plates having a transverse extent sufficient to span said cage and having an extension portion adapted to span at least a portion of a like cage positioned adjacent to said cage, said extension portion having at least one aperture adapted to receive a portion of an electrode assembly of said like cage, whereby two of said cages are each adapted to be separately assembled between said two of said spacer plates to form separate, self-supporting cages and then fixed with the other cage into a composite structure.

6. An electron tube comprising an envelope containing a plural cage mount including two electrode cages each including two spacer plates, one of the plates of each of said cages extending substantially only across one of said cages and contacting the inner wall of said envelope at one edge of said one of said plates, and the other of the plates of each of said cages spanning both of said cages and contacting opposite sides of said inner wall at opposite edges of said other of said plates.

7. An electron tube comprising an envelope containing a plural cage mount including two electrode cages each including two flat spaced-apart spacer plates, one of the plates of each of said cages extending substantially only across one of said cages and being spaced from the inner wall of said envelope and the other of the plates of each of said cages having an extension portion spanning the other of said cages and contacting opposite sides of said inner wall at opposite edges of said other of said plates, and with said extension portion of each of said other of said plates lapped over said one of said plates of the other cage, and each of said extension portions being fixed to the cage spanned by said portion.

8. A method of making an electron tube mount comprised of two elongated electrode cages each including an electrode assembly having at one end thereof a first spacer plate secured to and spanning only one of said cages and at the opposite end thereof a second spacer plate secured to and spanning both of said cages; said method comprising the steps of positioning said cages in axial alignment and with the electrode assemblies of each of said cages axially spaced and on opposite sides of a reference plane parallel to the axes of said cages and with said second plates of each of said cages adjacent to each other, moving said cages axially toward each other until each of said second plates contacts one of said first plates of the other cage, and fixing each of the contacting plates together to form a composite, two-cage mount.

9. A method of making an electron tube mount comprised of two elongated electrode cages each including an electrode assembly having at one end thereof a first spacer plate secured to and spanning only one of said cages and at the opposite end thereof a second spacer

plate secured to and spanning both of said cages; said method comprising the steps of positioning said cages in axial alignment and with the electrode assemblies of each of said cages on opposite sides of a reference plane parallel to the axes of said cages and with the ends of each of said cages having said first plate, facing in opposite directions; moving said cages axially toward each other until each of said second plates contacts one of said first plates of the other cage; and fixing each of the contacting plates together to form a composite, two-cage mount.

10. A method of making an electron tube mount comprised of two self-supporting, elongated electrode cages each including at opposite ends two flat spacer plates spaced the same distance apart as the spacer plates of the other cage, and an electrode assembly having electrode portions extending through the plates of its cage, and with a first of the plates of each of said cages extending substantially only across the cage and a second of the plates of each of said cages having an extension portion spanning the other of said cages and lapped over the first plate of said other of said cages, and with the spacer plate extension portion of each of said cages having apertures receiving therethrough the portions of the electrodes extending through the spanned cage; said method comprising the steps of positioning said cages in axial alignment and with said first plate of each cage adjacent to the first plate of the other cage and with the electrode assemblies of each of said cages axially spaced and on opposite sides of a reference plane parallel to the axes of said cages, and with said spanning portion of each of said second plates in axial alignment with said first plate of the other cage; moving said cages axially toward each other until each of said first plates contacts the second plate of the other of said cages and said electrode portions adjacent to said first plate of each cage extends through the apertures in the second plate of the other cage; and deforming at least some of said electrode portions for fixing adjacent spanned and spanning spacer plates together, whereby a composite, two-cage electron tube mount is formed.

11. A method of making an electron tube structure; said method comprising the steps of making two self-supporting, elongated electrode cages each including an electrode assembly having at one end thereof a first spacer plate spanning only one of said cages and at the opposite end thereof a second spacer plate spanning both of said cages; positioning said cages in axial alignment and with the electrode assemblies of each of said cages on opposite sides of a reference plane parallel to the axes of said cages and with the ends of each of said cages having said first plate, facing in opposite directions; moving said cages axially toward each other until each of said second plates contacts one of said first plates of the other cage; and fixing each of the contacting plates together to form a composite, two-cage structure.
